SHADING MACHINE

Filed June 26, 1928

A technical line drawing of a printing press mechanism. The base is a rectangular frame labeled 10. On top of the frame is a rectangular plate labeled 13. A horizontal bar labeled 25 is positioned above the plate. Two vertical posts labeled 11 are on the left, and two vertical posts labeled 12 are on the right. A horizontal bar labeled 33 is attached to the posts. A central horizontal bar labeled 27 is supported by a central vertical post labeled 28. A curved line labeled 29 points to a circular indentation on the plate 13. A horizontal bar labeled 14 is attached to the right side of the plate 13.

UNITED STATES PATENT OFFICE

WILLIAM MURPHY, OF BUFFALO, NEW YORK, ASSIGNOR TO RICHARD E. GAVIN, OF BUFFALO, NEW YORK

SHADING MACHINE

Application filed June 26, 1928. Serial No. 238,522.

This invention relates generally to portable shading machines but more particularly to the means for mounting the shading screen or medium thereon.

5 Its object is to provide a simple, reliable and inexpensive holder or clamping device for detachably connecting the frame or carrier of the shading medium to the machine, such means being constructed and arranged 10 to firmly secure the frame thereto and permit of its ready application and removal in a minimum period of time.

In the accompanying drawings:—

Figure 1 is a perspective view of a shading machine showing my improved holder applied thereto. Figure 2 is an enlarged sectional top plan view of the holder and its associated parts. Figures 3, 4 and 5 are transverse sections on the correspondingly 20 numbered lines in Figure 2.

Similar characters of reference indicate corresponding parts throughout the several views.

By way of example, my invention has been 25 shown in connection with a shading machine including a base 10 supported on a board 11 and adjustable to any desired height relative thereto by the upright corner posts 12. Adjustably mounted on the base for both lateral 30 and longitudinal movement relative thereto is a sliding plate 13 to the front end of which is joined the improved holder or clamping device, indicated generally by the numeral 14.

This holder is preferably composed of a 35 bottom plate or fixed jaw member 15 and a top plate 16, the front portion of the latter overhanging the former in the manner shown in Figures 3, 4 and 5 and its rear portion being secured to the bottom plate by screws 17, 40 which engage centering bosses 18 projecting downwardly from the top plate and seated in corresponding sockets 19 in said bottom plate. At its front and adjoining sides the top plate has a depending rim or flange 20. The 45 holder is hinged to swing vertically relatively to the sliding plate 13 of the machine and for this purpose the ends of its bottom plate 15 terminate in rearwardly-facing hinge lugs 21 carrying pivot pins 22 detachably engaging horizontally-swinging levers 23 pivoted

at 24 to said sliding plate and joined to each other by a coil spring 25 which tends constantly to urge the levers into engagement with the hinge pins 22. By swinging these levers outwardly, the holder may be readily 55 detached from the machine. The front wall of the bottom plate 15 of the holder is provided adjacent its ends with bearing faces 26 against which the back edge of the film or screen-carrying frame 27 is adapted to 60 bear, the screen or other shading medium 28 being glued or otherwise secured to the bottom of said frame.

Cooperating with the fixed jaw member 15 for securely holding the film-frame to the 65 holder is an opposing movable jaw 29 disposed centrally of the holder and adjustable transversely thereof toward and from the fixed jaw member. Said movable jaw is substantially T-shaped and is arranged beneath 70 the overhanging portion of the fixed jaw, its shank or rear portion 30 engaging a guide way 31 arranged between the contiguous top and bottom faces of the holder-plates 16 and 15, respectively, and preferably formed by a 75 recess or groove cut in the top face of the bottom plate. The head or front portion of the movable jaw engages a similar guide way 32 formed in the rim 20 of the top plate 16 and is provided at its front end with a depending gripping flange 33 for engaging the front edge of the attaching end of the screen-frame, as shown in Figures 1 and 4.

The shank 30 of the movable jaw terminates at its rear end in a depending lug 34 in 85 which an adjusting screw 35 is mounted, its front end bearing against the rear face of the holder-plate 15, as seen in Figure 4. Coil springs 36 are interposed between the fixed jaw plate and the head of the movable jaw 90 for urging the latter forwardly or away from the fixed jaw to permit of the insertion and removal of the screen-frame to and from the holder. Upon turning the adjusting screw in a counter-clockwise direction the 95 movable jaw is positively shifted rearwardly to grip the screen-frame, and upon turning the same in a clockwise direction the jaw is shifted forwardly by the springs 36 to release its grip on the frame. 100

By this construction and arrangement of parts, the screen-frame is reliably and firmly held in the holder through the medium of a three-point bearing, including the fixed jaw bearing faces 26 and the gripping flange 33 of the movable jaw 29. Furthermore, the tightening and loosening of the frame to effect its application and removal to and from the holder is accomplished by a fractional turn 5 of the adjusting screw 35.

10 I claim as my invention:—

1. A holder for the shading medium frames of shading machines, comprising a fixed jaw member having an overhanging front portion for receiving the rear edge and adjoining top side of the attaching end of the frame, a movable jaw slidably mounted on the fixed jaw and extending beneath its overhanging portion, the front end of said movable jaw 15 terminating in a depending gripping flange arranged to engage the opposing front edge of said frame and its rear end terminating beyond said fixed jaw member and having a lug thereon, and an adjusting screw carried by said lug and engaging the rear side of the fixed jaw member.

2. A holder for the shading medium frames of shading machines, comprising a fixed jaw member having an overhanging front portion for receiving the rear edge and adjoining top side of the attaching end of the frame, said jaw member having a guide way therein below the plane of its overhanging portion, an opposing jaw slidably in said 20 guide way and terminating at its front end in a depending gripping flange arranged to engage the opposing front edge of said frames and at its rear end beyond the fixed jaw member in a lug, an adjusting screw carried by said lug and engaging the rear side of said fixed jaw member, and a spring interposed between the latter and said movable jaw.

3. A holder for the shading medium frames of shading machines, comprising a plate adapted to be hingedly connected to the machine and including bearing faces for the rear edge and adjoining top side of the attaching end of the shading medium frame, a movable jaw slidably mounted substantially centrally of said plate and having a depending gripping flange in opposed relation to the rear edge bearing face of said plate and arranged to engage the front edge of said frame, an actuating screw for positively shifting the movable jaw to gripping position, and a spring for urging the latter to its released position.

WILLIAM MURPHY.
